UNITED STATES PATENT OFFICE.

ERNEST L. MARTIN, OF HOUSTON, TEXAS.

LANDING DEVICE FOR AEROPLANES.

1,352,077.

Specification of Letters Patent.

Patented Sept. 7, 1920.

Application filed February 26, 1920. Serial No. 361,496.

To all whom it may concern:

Be it known that I, ERNEST L. MARTIN, citizen of the United States, residing at Houston, in the county of Harris and State 5 of Texas, have invented certain new and useful Improvements in Landing Devices for Aeroplanes, of which the following is a specification.

This invention relates to new and useful 10 improvements in a landing device for aeroplanes.

One object of the invention is to provide a landing device of the character described which may be controlled by the aviator and 15 adjusted in accordance with the direction of movement of the plane at the time of landing.

In landing the machine often encounters 20 side winds which tend to force the plane laterally, subjecting the landing wheels to great side strain so that their anchorage is often broken and it is the object of this invention to provide a landing device which may be so adjusted in landing, as to relieve it from 25 the lateral strain caused by the wind blowing in a cross current relative to the direction of movement of the plane.

Another object of the invention is to provide 30 a landing device whose wheels are cushioned by means of a pneumatic cushion so that the shock and strain incident to landing is greatly relieved.

With the above and other objects in view, 35 the invention has particular relation to certain novel features of construction, operation and arrangement of parts, a description of which is given in this specification illustrated in the accompanying drawings wherein:

40 Figure 1 shows a rear view of the landing device,

Fig. 2 shows a perspective view thereof,

Fig. 3 shows a side view partially in section and

5 Fig. 4 shows a side view of an aeroplane with the landing device attached.

Referring now more particularly to the drawings wherein like numerals of reference designate similar parts, in each of the 0 figures, the numeral 1 designates the fuselage of the machine. Secured to this fuselage underneath and slightly in front of the wings or planes there is a rectangular frame work 2. Depending from the sides of this frame work are the A-frames 3, 3 which are

pivotedly connected to the frame work by means of universal joints 4; and these A-frames are held in fixed relation to each other by means of a cross link 26, which is pivoted at its ends to said frames. The rear arm of 60 each A-frame consists of a cylinder 5 in which there is fitted a piston 6. This piston is rigidly attached to the inner end of the rod 7 which operates through a stuffing box 8 carried by the lower end of the cylinder. 65 The lower end of each rod is bifurcated forming the spaced fingers 9, 9 and rotatably mounted between these respective fingers are the landing wheels 10, 10. The upper end of each cylinder has an inlet valve 11 through 70 which a sufficient amount of lubricating oil may be introduced into the cylinder and there is a by pass 12 provided to permit any oil which escapes past piston to find its way back into cylinder above the piston. 75

A shaft 13 is rotatably mounted in end bearings 14 carried by the respective ends of the frame work 2 and fixed to said shaft inside of its respective bearings are small sprocket wheels 15, 15. Anchored to the 80 frame work on opposite sides at each end are the pulleys 16, 16 and operating over these respective sets of pulleys are the cables 17, 17, the ends of each cable being crossed and being attached to the lower part 85 of the opposite A-frame. A section of each cable, as 18, is formed into a sprocket chain which operates over the corresponding sprocket wheel 15.

In front of the aviator there is a rotatably 90 mounted steering shaft 19, whose rear end has the steering wheel 20, fixed thereon. This shaft has the fixed sprocket wheel 21 in alignment with the corresponding sprocket wheel 22 fixed on the shaft 13, and 95 operating over these sprocket wheels there is a sprocket chain 23 through which rotation is imparted from the shaft 19 to the shaft 13.

It is obvious that by the manipulation of 100 the hand wheel 20 the position of the landing device may be varied, as indicated in dotted lines in Fig. 1, and the angle thereof relative to the aeroplane may be readily changed, so as to relieve said device from 105 unnecessary side strain in alighting; due to cross currents of the wind.

Extending rearwardly from the lower end of each of the rods 7 are the downwardly curved stabilizers 24 whose free ends are 110

formed into plate like projections 25 which cut into the surface of the ground and hold the steering wheels 10 to a direct course.

What I claim is:

- 5 1. The combination with an aeroplane, of a landing device depending therefrom and including landing wheels pivotally connected to the fuselage and means for simultaneously adjusting said wheels laterally, in
- 10 the same direction.
- 2. The combination with an aeroplane of a landing device including laterally swinging frames, spaced apart and depending from the fuselage, landing wheels anchored
- 15 to the frames and a device for simultaneously moving both frames laterally in either direction relative to the fuselage.
- 3. The combination with an aeroplane, of a landing device including landing wheels,
- 20 a pneumatic cushioning device through

which each wheel is suspended from the fuselage, and means through which both wheels may be simultaneously moved laterally in either direction relative to the fuselage.

25 4. A landing device for aeroplanes including wheel supports pivoted to and depending from the fuselage and spaced apart, a wheel carried by each support and a manual mechanism for simultaneously swinging said supports laterally in the same direction.

30 In testimony whereof I have signed my name to this specification in the presence of two subscribing witnesses.

ERNEST L. MARTIN.
